UNITED STATES PATENT OFFICE.

WILLIAM B. SHEDD, OF NEW YORK, N. Y., ASSIGNOR, BY DIRECT AND MESNE ASSIGNMENTS, OF THREE-FOURTHS TO JOHN METZ, OF JERSEY CITY, NEW JERSEY, AND S. C. FORSAITH & CO., OF MANCHESTER, N. H.

PRINTING-PRESS.

SPECIFICATION forming part of Letters Patent No. 286,337, dated October 9, 1883.

Application filed August 7, 1882. (No model.)

To all whom it may concern:

Be it known that I, WILLIAM B. SHEDD, of the city, county, and State of New York, have invented a new and useful Improvement in 5 Printing-Presses; and I hereby declare the following to be a full and clear description of the same.

The object of this invention is to construct a printing-press of the class known as "job- 10 presses," with the least possible cost, both as to labor and material, and to so dispose, construct, and operate the mechanism of the press that the movable platen will receive and carry the paper to be printed on up to the face of 15 the type with great speed, regularity, and exactness, and then stop and hold the paper in position to receive the impression, while the bed moves slightly forward, so as to give the impression with great force, both the bed and 20 platen of the press being at the time of the impression held or forced together by means of thrust-rods, the fulcrums of which are held together by means of tie-rods crossing the machine at the ends of the bed and platen, and 25 acting in planes perpendicular, or nearly perpendicular, to the vertical faces thereof.

The nature and details of the invention will fully appear from the subjoined specification, and from the accompanying drawings, of 30 which—

Figure 1 is a transverse sectional elevation of the machine, taken just in front of the operating or cam shaft, from which the different mechanisms of the press are driven. This 35 view shows only the general mechanism for moving the bed and platen. All other parts are removed for perspicuity. Fig. 2 is a general plan of the machine or press. Fig. 3 is an end elevation of it. Fig. 4 is a longitudinal 40 sectional elevation of the press or machine, taken on the line $x-x$ of Fig. 2. Fig. 5 is a longitudinal sectional elevation of the press or machine, taken on the line $y-y$ of Fig. 2. Fig. 45 6 is a transverse sectional elevation of the press or machine, taken on the line $z-z$ of Fig. 2. Fig. 7 is a detail view of the eccentric-pin which couples the rear thrust or impression rod to the bed.

The frame of this machine consists of two side plates, A A, with transverse beams A', 50 and such other connecting parts and appendages as may be required to hold the machine together or provide bearings for its operative parts. Principal among these appendages or other parts of the frame are two fulcrum-beams, B and B', and two tie-rods, C, which hold the said fulcrum-beams together and take up the thrust of the compression-levers or followers at the moment of the printing-impression. The beams B B' and their tie-rods C form 55 a nearly rectangular frame, which rests on, and is supported by, the side plates, A.

The printing operation is performed by and between the bed and platen D E, which are moved and operated as hereinafter described. 60 The whole moving mechanism of the press will be operated by and from the driving-shaft F, the outer end of which carries the fast and loose pulleys $f-f'$, to which the driving-belt is applied. The counter-shaft G, which carries 65 several operating-cams, as hereinafter described, has its bearings in the pillow-blocks $a-a$ of the two principal side plates, A A, and its location is such as to place it about in the transverse center of the machine. The said 70 counter-shaft G is driven by the gear-wheel G' on its outer end, and receives its motion from the driving-gear wheel F' of the driving-shaft F. The rock-shaft H also has its bearings in 75 suitable pillow-blocks formed on or secured to the frame-plates A A, and this rock-shaft is driven or operated from and by the counter-shaft G, in the manner presently explained. The bed D, which supports and also moves the type during the printing operation, has a seat, 80 d , for receiving and holding in position the type, and it is supported on the tie-rods C by means of the end lugs, d' and d'' , which are slotted so as to readily fit and slide on the said rods C, as shown in Figs. 1 and 2. The sliding movement of the said bed upon the rods C is very limited, being only just enough to readily give the impression, and not more than about half an inch is required for this purpose. The normal position of the bed D 85 will be back—*i. e.*, the position farthest re- 90 95

moved from the platen E—and it will be habitually held in that position (except when moved forward by the levers hereinafter described) by means of the retaining-springs I 5 I, which in the drawings are represented as coiled springs, surrounding the rods C, and abutting against lugs or collars a', that are attached to and project from the frame-rods C. The bed D is moved forward by the cam D' on 10 the counter-shaft G acting on and moving the lever D², which actuates the connecting-rod D³, and this connecting-rod actuates the lever D⁴, which, in turn, moves the follower or thrust rod D⁵, the forward end of which presses 15 against the assembling-pin D⁶, which is seated in flanges or other attached portions of the said bed D. The backward and forward positions of the bed D, and the corresponding positions of the actuating mechanism above mentioned, and connected therewith, are respectively shown in Figs. 5 and 6 of the accompanying drawings. The lever D⁴, which moves the follower or thrust rod D⁵, is fulcrumed on the bearing-block b of the fulcrum-beam B. 20 The distance between the point of bearing of the lever D⁴ on its fulcrum b, and the bearing point d² on the same lever, against which the thrust-rod D⁵ rests, is very short, and the movement of the said lever is considerable, 25 so that the force of the said lever, in pressing against the follower or thrust rod D⁵, is very great, and the pressure thus brought to bear against the bed D is such as to produce a very strong or powerful impression of the type 30 which are secured to the said bed D. The prime lever D² of this series has its outer end pivoted or fulcrumed to a suitable part of the frame of the press, as is represented by the lug a², attached to the cross-beam A' of Figs. 35 5 and 6. A roller or sheave, d¹, journaled to the side of the said lever D², in its central part, rolls against and is actuated by the cam D', the said cam being so constructed that at each rotation of its shaft G it moves the primary 40 lever D² and its attachments up and down twice, thus making two complete reciprocating movements at each rotation of the said cam-shaft. The free or reciprocating end of the lever D² is attached, by means of a suitable 45 coupling-pin, to the lower end of the connecting-rod D³, and the top end of this connecting-rod is in like manner connected with the free end of the lever D⁴, and thus this system of compound levers is connected and actuated 50 for the proper reciprocating movement of the bed D, and the said bed, in accordance with the movements of the actuating-lever mechanism above described, makes two complete reciprocating movements at each rotation of the 55 cam-shaft G. The platen E is pivoted at e to a suitable part of the press-frame, so that it may be turned down into a sloping and nearly flat position, as shown in Fig. 5, or raised up into a vertical position, as shown in Fig. 6. 60 While in the first named of these positions the paper is placed on the said platen, and

while in the second named or vertical position the paper disposed on the said platen is printed upon or receives an impression from the type which are attached to the bed D. The platen 70 E is moved from one of the above-named positions to the other position, and vice versa, by means of a system of levers and rods actuated by the cams E', which are fixed to and rotated by the shaft G. The said cams E' 75 actuate the levers E², the levers E² actuate the connecting-rods E³, and the connecting-rods E³ move the sliding heads E⁴ up and down, and carry the platen E along with them, as the said sliding heads move in ways which are fixed to 80 the outside of the said platen. In this manner the said platen E is moved into its open and closed positions, as shown respectively in Figs. 5 and 6. The levers E² of this series of mechanism are fulcrumed to a suitable part of the 85 press-frame, as is represented by the lugs a³, attached to the cross-beam A' of Figs. 5 and 6. A roller or sheave, e¹, journaled to the side of each of the said levers E², in its central part, rolls against and is actuated by one of the cams 90 E', the said cams being so constructed that at each rotation of the shaft G they move the said levers E² and their attachments up and down twice, thus making two complete reciprocating movements at each rotation of the said 95 cam-shaft. The sliding heads E⁴ are arranged to move in suitable ways, e², attached to the outside of the platen E. The connecting-rods E³ have their upper and lower ends, respectively, assembled to the sliding heads E⁴, and 100 to the free or reciprocating ends of the levers E², by means of suitable cylindrical assembling-pins. In this manner the said platen E is moved into its lower and upper positions twice at each revolution of the cam-shaft G, 105 and it is held firmly in its vertical or printing position by means of the hinge pivot-pin e and by the followers or thrust-rods E⁵. One end of each of said followers or thrust-rods E⁵ is pivoted to the sliding heads E⁴ by the same 110 pins that assemble the upper ends of the connecting-rods E³ to it, and the other end of each follower is fulcrumed on the bearing-block b' of the beam B'. This mechanism is clearly 115 shown in Figs. 5 and 6. It permits the followers or thrust-rods to allow the platen E to lower down into the open position shown in Fig. 5, and also assume the vertical position shown in Fig. 6; and when in the latter position the said followers or thrust-rods will press 120 against the platen E, in a line perpendicular to its printing-face, and in the same plane as that occupied by the axes of the tie-rods C, the beams B and B', and the followers or thrust-rod D⁵, as is clearly shown in Fig. 6, thereby 125 throwing all the strain exerted in opposite directions by the followers D⁵ and E⁵ at the supreme moment of their action upon the tie-rods C and their cross beams B and B'. This construction, as is self-evident, secures the greatest 130 possible amount of strength for the least possible amount of material, and insures the print-

ing-impressions between the bed and platen D and E firm, full, and certain. As is shown in the drawings, there is one follower, D⁵, and two of those marked E³, with their respective actuating mechanisms; but, of course, there may readily be substituted for this arrangement one or more of each of the said systems. The rock-shaft H is moved in harmony with the other parts of the machine by means of the 10 driving-cam H' on the counter-shaft G. This cam actuates the lever H² by engaging against the sheave h, journaled to the side of the said lever in a manner similar to that described for the prime levers D² and E². One end of the 15 said lever H² is fulcrumed to the press-frame by means of the lugs a⁴ in a manner similar to the fulcruming of the levers D² and E². The other or reciprocating end of the lever H² is assembled to the lower end of the connecting- 20 rod H³ by means of a suitable pin, and the upper end of the said connecting-rod is also attached, by means of a suitable pin, to the outer or free end of the crank H⁴ of the rock-shaft H. By means of this mechanism the 25 said rock-shaft is rocked back and forth by the cam H' twice at each rotation of the said cam. The rock-shaft H is used to operate the ink-rollers—*i. e.*, move them up and down over the face of the type—which are fixed to the 30 face of the bed D. These ink-rollers K are attached to a sliding head, k, that moves in ways k' up and down as required for receiving ink from the ink-feeding roller L and distributing the ink over the faces of the type secured to the seat d. The ways k' are formed partly 35 in the outside faces of the upper ends of the frame-plates A, and partly in the outer ends of the bed D. The said ends of the bed project through a recess in the said frame-plates A, and are simply grooved, so as to form the 40 ways k'. When the bed D is thrown back to its normal seat, the ways k', which are formed on its ends, will be in alignment with that portion of the said ways which are formed on the 45 plates A; but when the said bed D is thrown forward to its impression position, the said ways k', which are formed on it, will be carried along with it; but as the mechanism for operating the rock-shaft H is such as to move the 50 sliding head up and down only when the platen or bed D is moved to its rear or normal position, this break of the continuity of the ways k' will be of no importance. The sliding head k, to which the ink-rollers K are attached by 55 means of spring-rod k², is moved by the rock-shaft H through the medium of the actuating-arms K' and the connecting-rod K². The actuating-arms K' are fixed to the rock-shaft H, and move with it, and the connecting-rod

K² has its upper and lower ends, respectively, 60 attached to the sliding head k and to the actuating-arm K' by means of suitable assembling-pins. This mechanism is so constructed as to cause the ink-rollers to rise up to the top of their ways, and then run down to the bottoms 65 of their ways, and remain stationary there during one forward and backward movement of the bed D, thus causing the inking-rollers to pass twice over the faces of the type at each impression. The assembling or thrust pin D⁶ 70 is made in the form of a shaft, which extends, at one end at least, to the outside of the follower or bed D, in which it has its bearings. The central or bearing part of this pin or rod against which the follower or thrust rod D⁵ 75 rests is made eccentric in form, so that when the full side of it is in contact with the said follower or bed D, the said follower-rod can push it home against the platen E; but when the scant side of it is in contact with the said 80 follower, the follower cannot push the follower or bed D home against the platen E. The overhanging end of the pin or rod D⁶ is attached to a lever or crank, M, and the outer end of this crank is attached to a connecting-rod, m, 85 the forward end of which said connecting-rod is attached to a hand-lever, M', by the side of and at the front of the machine. The press-feeder can at any moment draw the lever M' forward, and thereby prevent the bed D from 90 completing a full stroke up to and against the platen E, and in this manner the pressman can prevent the spoiling of a sheet of paper that may have been misplaced on the press.

Having described my invention, I claim— 95

1. In a printing-press, the compression-frame B B' C, provided with bearings b b', in combination with a reciprocating press-bed and oscillating platen, the followers or thrust-rods D⁵ E³, the lever D⁴, vertically-sliding 100 heads E¹, and suitable operating mechanism, substantially as shown and described.

2. In a printing-press, the oscillating platen E, sliding heads E¹, thrust-rods E³, connecting-rods E², levers E², cams E', and shaft G, substantially as shown and described. 105

3. In a printing-press, the combination of reciprocating press-bed D, eccentric-shaft D⁶, crank M, rod m, and hand-lever M', thrust-rod D⁵, lever D⁴, and actuating devices, with 110 the oscillating platen E, and operating mechanism, and the rigid frame B B' C, substantially as shown and described.

WM. B. SHEDD.
